BELT BUCKLE

Clifford A. Spanganberg, Rochester, N. Y., assignor to Hickok Manufacturing Co., Inc., Rochester, N. Y., a corporation of New York

Application April 25, 1949, Serial No. 89,518

10 Claims. (Cl. 24—176)

1

This invention relates to belt buckles. The invention more particularly relates to an initial belt buckle.

Heretofore, belt buckles have been provided with one or more initials on the face thereof. The initial or initials, however, in the prior belt buckles were either embossed or otherwise imprinted on the face of the buckle or one or more initials were inserted in a depressed or cut out portion on the face of the buckle.

In the prior belt buckles, therefore, it will be seen that the initial or initials were simply a part of the actual face of the buckle or on the face of the buckle. Thus a definite face portion of the buckle is provided to hold or carry the initials thereon.

In the present belt buckle, there is no face portion thereof as such. The face portion of the present belt buckle is the initial, letter of the alphabet or other indicia itself which is cut-out to more clearly define the same and to allow the portion of the belt behind same to provide a background therefor. In other words, the initial of the present belt buckle constitutes the face portion thereof and when this face portion in the form of the initial is attached to a base portion, in spaced relationship to the latter, the free end of the belt passes in that space portion between the rear side of the initial and the front side of the base of the buckle and forms a background for the cut-out portion or portions of the initial, letter of the alphabet or other cut-out indicia.

In the present buckle, the base portion is so formed that any one of the cut-out letters of the alphabet or other indicia or an emblem or the like may be readily secured thereto and constitute the entire or sole face portion of the buckle.

This belt buckle is so formed that when the buckle is on display or in use the only exposed part thereof will be the initial or letter of the alphabet which constitutes the entire or sole face of the buckle.

With the foregoing in mind, it is an object of the invention to provide a belt buckle wherein the face portion thereof is in the form of an initial.

Another object of the invention is to provide a buckle consisting of a base portion and an initial or the like which constitutes the entire or sole face of the buckle, the said base and initial being associated with each other so that the free end portion of the belt passes between the base portion and the rear side of the initial.

Another object of the invention is to provide

2

a belt buckle wherein the face portion is in the form of an initial and when the belt is in use the only portion thereof that is visible is the said initial.

5 Another object of the invention is to provide a belt buckle wherein the entire exposed face portion thereof is in the form of an initial.

Another object of the invention is to provide an initial belt buckle whereby the initial may be readily secured to the base of the buckle and maintained in proper relationship with respect to the base.

Another object of the invention is to provide 15 a common belt buckle base so that any one of the letters of the alphabet may be readily secured to that base.

Another object of the invention is to provide 20 an initial belt buckle which is highly practical and simple and inexpensive to manufacture and yet being highly ornamental.

Another object of the invention is to provide 25 a belt buckle consisting of a rear and face portion connected together so as to define a through passageway for a free end of a belt therebetween and wherein the face portion of the buckle is at least co-extensive in width with the rear portion thereof and the said face portion consists entirely or solely of suitable cut-out indicia so that the free end portion of the belt back 30 of the indicia forms a background therefor and, of course, where the belt buckle has associated therewith means to which one end of the belt is secured thus securing the belt to the buckle or vice versa.

35 With the above objects in mind, the invention consists in the construction and novel combination and arrangement of parts hereinafter fully described, illustrated in the accompanying drawings and pointed out in the claims hereto appended, it being understood that various changes in the form, proportions, and minor details of construction, within the scope of the claims, may be resorted to without departing from the spirit or sacrificing any of the advantages of the invention.

40 In the drawings wherein like numerals in the several figures thereof denote the same parts:

Fig. 1 is a front elevational view of the initial buckle.

Fig. 2 is a rear elevational view of the buckle.

Fig. 3 is a top plan view.

Fig. 4 is a longitudinal cross sectional view 45 of the line 4—4 of Fig. 1 of the buckle showing the buckle attached to a belt and with the free end of the belt passing through the buckle.

Fig. 5 is a vertical sectional view of the buckle taken on the line 5—5 of Fig. 1;

Fig. 6 is a perspective view of the rear portion or back plate or base of the buckle; and,

Fig. 7 is a perspective view of one initial or letter of the alphabet constituting the face of the buckle.

The invention will be more readily understood by referring to the drawings in detail. The buckle denoted generally at B consists of two integral parts; namely, a base or rear portion C and the cut-out initial or letter D or the like constituting the entire or sole front face thereof.

The base portion C of the buckle is of generally rectangular shape and is preferably fabricated from metal, precious or other metal or alloys or other suitable material and includes and has on its front side 8 substantially diametrically disposed elongated recesses or depressions 9 and 10 adjacent the upper right corner thereof and the lower left corner thereof, respectively. These recesses or depressions 9 and 10 on the face 8 of the base of the buckle result in similarly shaped elongated embossures 11 and 12, respectively, on the rear face 13 of the buckle base. A belt attaching eye or loop 14 is formed integral with and extends at a slight angle with respect to one end of the base of the buckle. The upper and lower portions 15 and 16 of the eye or loop 14 are in the form of inwardly directed flanges 17.

As stated, the eye or loop 14 at one end of the base of the buckle is inclined with respect to the base of the buckle as will be clearly seen in Figs. 3, 4 and 6 and this inclination with respect to the base of the buckle is provided so that when the end of the belt is attached to the eye by means of looping the same therethrough the space between the inclined portion and the face of the base of the buckle will be sufficient to allow the turned over attached end of the belt to be disposed in that space and when the free end of the belt is inserted through the buckle, it will lie in substantially the plane of the base of the buckle and not project forwardly when the belt is about the body of the user and which is hereinafter more fully described.

The other extreme end 18 of the buckle has a tongue 19 integral therewith. This tongue is in the form of a hook that extends forwardly as at 20 from the extreme edge or end of the buckle base and then is turned as at 21 at a right angle to the base and finally turned or bent as at 22 substantially parallel with and spaced from the base. This tongue structure provides in effect a hook which engages in a selected opening in the belt as hereinafter described.

The initial D which constitutes the front or face portion of the belt buckle, may be any initial or letter of the alphabet or other indicia such as an emblem or the like. This particular initial D is the letter "R" of the alphabet and, of course, this letter is shown for illustrative purposes only. The initial D is of the cut out type; namely, that there is a cut out portion 23 and another cut out portion 24. Of course, different letters of the alphabet will necessitate different cut out portions. However, any initial or letter may be used just so long as that initial, letter, emblem or the like constitutes the face portion of the buckle and that portion being that which is exposed when the buckle is properly attached to a belt in use. The particular initial shown has its exterior contour 25 beveled, which beveling 26 is correspondingly carried out in the cut-out portions of the initial or letter. The portion 27 which 75

is in between the aforesaid beveled portions of the initial is preferably flat any may be suitably ornamented, as by hammering or enameling for color, etc.

As seen in Fig. 7, the initial D has upper and lower right angularly disposed flanges 28 and 29, respectively, and integral with these flanges 28 and 29 there are integral upper and lower webs or attaching plates or members 30 and 31, respectively, and which webs or attaching members are substantially parallel with the face of the letter or initial.

The webs or attaching plates 30 and 31 which are elongated substantially correspond in shape 15 with the diametrically disposed recesses or depressions 9 and 10 in the base of the buckle. Here it will be noted that the letter or the initial is slanted with respect to the vertical when the buckle is viewed in front elevation and thus the 20 attaching plates or webs 30 and 31 are out of vertical alignment, so to speak, so that they may be disposed and secured in the said recesses or depressions 9 and 10 in the base of the buckle. The manner of securing the initial by means of 25 the webs or plates 30 and 31 in the recesses or depressions 9 and 10 may, indeed, be varied. One means of securing the initial and the base of the buckle together is by soldering as indicated at 30 or, of course, the solder may be disposed between the walls of the recesses or depressions 9 and 10 and the flat faces of the webs or plates 30 and 31. Soldering is merely mentioned as exemplary of one means of securing the belt to the base. The main object, of course, is to 35 suitably carry or associate the initial which constitutes the face of the buckle with the base of the buckle.

When the initial or letter is secured to the base of the buckle, as hereinbefore described, by means of soldering or otherwise attaching the webs or plates 30 and 31 in the recesses or depressions 9 and 10, there will in effect be present a substantially flat inner side of the base of the buckle as the gauge of the metal of the webs or plates 30 and 31 is of substantially the same depth as the depressions 9 and 10 wherein these webs 30 and 31, respectively, are secured. Thus, there is adjacent each of the recesses or depressions substantially flat portions 33 and 34 of the base of the buckle that are connected by the intermediate portion 35.

With reference to Fig. 4 wherein the buckle is shown attached to a belt or vice versa, the belt is denoted generally at 36 and this belt may be of leather or other suitable material and must, of course, possess flexible characteristics. The end 37 of the belt is inserted through the eye 14 at one end of the buckle base and is turned over on itself at 38 and stitched at 39 thereby securing that end of the belt to the buckle or vice versa. Usually, there is a slide or loop 40 at the attached end of the belt and this loop or slide for the free end of the belt may also be of leather or suitable material and is preferably secured at the end of the belt by means of the aforesaid stitching 39. The free end of the belt 41, as will be noted in Fig. 4, has been inserted between the inner face of the buckle rear portion C and the inner face of the face portion D, as indicated at 42, and which end of the belt is provided with a series or plurality of openings 43, any one of which openings may be selected to have entered therethrough the buckle tongue 19, thus securing the free end of the belt to the buckle. It will further be noted in Fig. 4 of the drawings that

5

the inclined or off-set eye 14 which is attached to the end of the belt is such that when the belt is worn the turned over end portion of the belt which is attached to the eye will not project or protrude forwardly and be unsightly when in use. This inclining or off-setting of the eye 14 of the buckle provides the space necessary between the free end of the belt and the attached end of the belt so as to prevent any protruding forwardly of the attached end of the belt when in use.

One rather wide letter or initial constituting the face of the buckle is shown. It is obvious, however, that two or more narrow initials or letters may be combined and constitute the face of the buckle.

From the foregoing, it is believed quite clear that a highly practical belt buckle is provided and wherein the buckle consists of only the two integral elements; namely, the base of the buckle and the initial which constitutes the front or face portion of the buckle and which initial or letter only is visible when the belt buckle is in use on a belt.

I claim:

1. A belt buckle consisting of a substantially rectangularly shaped rear portion having oppositely disposed end edges, a loop at one of the said end edges, a hook at the other of the said end edges, a face portion of the buckle including substantially right angularly disposed flanges at the top and bottom edges thereof, the said flanges terminating in integral webs that are disposed in spaced parallel relationship with the said face portion, means for securing the webs to the rear portion of the buckle so that the face portion thereof is in the said spaced relationship to the said rear portion to define a through passageway for a free end of a belt therebetween, and the said face portion of the buckle being at least co-extensive in width with the rear portion and consists solely of cut-out indicium whereby the portion of the free end of the belt back of the indicium forms a background therefor.

2. A belt buckle consisting of a substantially rectangularly shaped rear portion having oppositely disposed end edges, a loop at one of the said end edges, a face portion of the buckle including substantially right angularly disposed flanges at the top and bottom edges thereof, the said flanges terminating in integral webs that are disposed in spaced parallel relation with the said face portion, means for securing the webs to the rear portion of the buckle so that the face portion thereof is in the said spaced relationship to the said rear portion to define a through passageway for a free end of a belt therebetween, belt retaining means carried by said rear portion and engageable with the free end of a belt for holding the same in said passageway, the said face portion of the buckle being at least co-extensive in width with the rear portion and comprises cut-out indicium whereby the portion of the free end of the belt back of the indicium forms a background therefor, and wherein the rear portion of the buckle is provided with spaced depressions and the said webs of the face portion of the buckle are seated and secured in the said depressions.

3. A belt buckle consisting of a rigid elongated rear plate-like member having opposite end edges and including a face portion thereof, a loop integral with and extending outwardly from one of the end edges, a hook integral with the rear member and extending outwardly from the face thereof, a face member of the buckle including a sub-

6

stantially right-angularly disposed flange at the top and bottom edges thereof, the flanges terminating in integral webs that are disposed in spaced parallel relationship with the said face member, means for securing the webs to the rear member of the buckle so that the face member thereof is in the said spaced relationship to the said rear member to define a through passageway for a free end of a belt therebetween, the said face member of the buckle being at least coextensive in width with the rear member and consists solely of cut-out indicium, whereby the portion of the free end of the belt back of the indicium forms a background therefor, and the hook is adapted to engage a portion thereof and hold the free end of the belt.

4. A belt buckle consisting of a rigid elongated rear plate-like member having opposite end edges and including a face portion thereof, a loop integral with and extending outwardly from one of the end edges, a hook integral with the rear member and extending outwardly from the face thereof, a face member of the buckle including a substantially right-angularly disposed flange at the top and bottom edges thereof, the flanges terminating in integral webs that are disposed in spaced parallel relationship with the said face member, means for securing the webs to the rear member of the buckle so that the face member thereof is in the said spaced relationship to the said rear member to define a through passageway for a free end of a belt therebetween, the said face member of the buckle being at least coextensive in width with the rear member and consists of a cut-out letter of the alphabet, whereby the portion of the free end of the belt back of the letter of the alphabet forms a background therefor, and the hook is adapted to engage a portion thereof and hold the free end of the belt.

5. A belt buckle consisting of an elongated rigid plate-like rear member having oppositely disposed end and side edges and a front face portion, a loop at one of the said end edges and projecting therebeyond at an angle with respect to the plate-like rear member and integral therewith, a hook integral with the rear member and extending outwardly beyond its front face portion, a face member of the buckle having a substantially right-angularly disposed flange at the top and bottom edges thereof, the flanges terminating in integral webs that are disposed in spaced parallel relationship with the face member, the rear member having oppositely disposed elongated depressions in the face portion thereof and which depressions are open at the said opposite side edges and on the face portion thereof and are substantially of the same shape and proportions as the said webs and with the webs seated and secured in the said depressions so that the face member of the buckle is in the said spaced relationship to the rear member to define a through passageway for a free end of a belt therebetween, the said face member of the buckle being at least coextensive in width with the rear portion and consists of cut-out indicium, whereby the portion of the free end of the belt back of the indicium forms a background therefor, and the hook is adapted to engage a portion thereof and hold the free end of the belt.

6. A belt buckle consisting of an elongated rigid plate-like rear member having oppositely disposed end and side edges and a front face portion, a loop at one of the said end edges and projecting therebeyond at an angle with respect to the plate-like rear member and integral there-

with, a hook integral with the rear member and extending outwardly beyond its front face portion, a face member of the buckle including a substantially right-angularly disposed flange at the top and bottom edges thereof, the flanges terminating in integral webs that are disposed in spaced parallel relationship with the face member, the rear member having oppositely disposed elongated depressions in the face portion thereof and which depressions are open at the said opposite side edges and on the face portion thereof and are substantially of the same shape and proportions as the said webs and with the webs seated and secured in the said depressions so that the face member of the buckle is in the said spaced relationship to the rear member to define a through passageway for a free end of a belt therebetween, the said face portion of the buckle being at least coextensive in width with the rear portion and consists solely of a cut-out letter of the alphabet, whereby the portion of the free end of the belt back of the letter of the alphabet forms a background therefor, and the hook is adapted to engage a portion thereof and hold the free end of the belt.

7. A belt buckle consisting of a substantially rectangularly shaped rear portion having oppositely disposed end edges, a loop at one of the said end edges, a hook at the other of the said end edges, a face portion of the buckle including substantially right-angularly disposed flanges at the top and bottom edges thereof and said flanges terminating in integral webs that are disposed in spaced parallel relationship with the said face portion, means for securing the webs to the rear portion of the buckle so that the face portion thereof is in the said spaced relationship to the said rear portion to define a through passageway for a free end of a belt therebetween, and the said face portion of the buckle being at least coextensive in width with the rear portion and consists solely of a cut-out letter of the alphabet, whereby the portion of the free end of the belt back of the letter of the alphabet forms a background therefor, and the hook is adapted to engage a portion thereof and hold the free end of the belt.

8. A belt buckle consisting of a substantially rectangularly-shaped rear plate-like member having oppositely disposed end edges, a loop at one of the end edges and projecting therebeyond and integral therewith, a hook at the other of the end edges and projecting therebeyond and integral therewith, a face member of the buckle including a substantially right-angularly disposed flange at the top and bottom edges thereof, the flanges terminating in integral webs that are disposed in spaced parallel relationship with the said face member, means for securing the webs to the rear member of the buckle so that the face member thereof is in the said spaced relationship to the rear member to define a through passageway for a free end of a belt therebetween, the said face member of the buckle being at least coextensive in width with the rear member and consists solely of a cut-out letter of the alphabet, whereby the portion of the free end of the belt back of the letter of the alphabet forms a back-

ground therefor, and the hook is adapted to engage a portion thereof and hold the free end of the belt.

9. A belt buckle consisting of a substantially rectangularly shaped rear plate-like member having oppositely disposed end edges, a loop at one of the end edges and projecting therebeyond and integral therewith, a hook at the other of the end edges and projecting therebeyond and integral therewith, a face member of the buckle having a substantially right-angularly disposed flange at the top and bottom edges thereof, the flanges terminating in integral webs that are disposed in spaced parallel relationship with the said face member, means for securing the webs to the rear member of the buckle so that the face member thereof is in the said spaced relationship to the rear member to define a through passageway for a free end of a belt therebetween, the said face member of the buckle being at least coextensive in width with the rear member and consists solely of suitable cut-out indicium, whereby the portion of the free end of the belt back of the indicium forms a background therefor, and the hook is adapted to engage a portion thereof and hold the free end of the belt.

10. A belt buckle comprising an elongated rigid rear member having oppositely disposed end and side edges and a front face portion, a loop at one of the said end edges and projecting therebeyond to provide a belt receiving opening so that a belt can be attached to said loop, a front member of said buckle having a substantially right-angularly disposed flange at the top and bottom edges thereof, the said flanges terminating in integral webs that are disposed in spaced parallel relationship with the front member, said rear member having oppositely disposed elongated recesses at the opposite side edge portions, said recesses being open at the opposite side edges, said webs being seated and secured in the said recesses so that the front member of the buckle is in spaced relationship to the rear member to define with said flanges a through passageway for a free end of the belt therebetween, and a fixed member carried by said rear member and extending forwardly of said rear member into the path of the passageway for a free end of the belt for engagement therewith to retain the same in position, and the said front member of the buckle being at least coextensive in width with the rear portion and comprises at least one cut-out indicium whereby the portion of the free end of the belt back of the indicium forms a background therefor.
